RIVET FEEDING DEVICE

Lloyd G. Speth, Cleveland, Ohio, assignor to The
Cleveland Pneumatic Tool Company, Cleveland,
Ohio, a corporation of Ohio

Application August 26, 1943, Serial No. 500,103

10 Claims. (Cl. 78—46)

This invention relates to devices for manually inserting rivets or the like into work openings and aims to provide a device of this kind which is more satisfactory and efficient than previous devices and is less likely to become jammed or to cause marring of the work.

Another object of this invention is to provide an improved device of this character having a tube adapted to contain a plurality of rivets and novel means for releasing the rivets from the delivery end of the tube.

A further object of the invention is to provide an improved device of this kind in which resilient fingers for retaining the rivets in the tube are adapted to be engaged and spread by the delivery end of the tube for releasing the rivets therefrom.

Still another object of the invention is to provide an improved device of the character mentioned in which the tube and a thrust member engageable with the work are relatively movable for causing spreading of the resilient fingers and in which the thrust member is of a form such that it is not likely to cause marring of the work.

The invention may be further briefly summarized as consisting in certain novel combinations and arrangements of parts hereinafter described and particularly set out in the appended claims.

In the accompanying sheets of drawings,

Fig. 1 is a perspective view showing a rivet placing device constructed according to the present invention.

Fig. 2 is another perspective view of the device but with the cover thereof in its open position.

Fig. 3 is a partial longitudinal sectional view taken through the work-engaging or delivery end of the device and showing a rivet as having just been inserted into a work opening.

Fig. 3a is a detail longitudinal sectional view taken substantially at right angles to that of Fig. 3.

Fig. 4 is a partial perspective view showing a modified form of my rivet placing device.

Fig. 5 is a partial longitudinal sectional view thereof and showing a rivet as having just been inserted into the work opening.

Fig. 6 is a partial perspective view of another modified form of the device.

Fig. 7 is a partial longitudinal sectional view thereof and showing the same just after the insertion of a rivet into the work opening.

Fig. 8 is a partial perspective view showing still another modified form of the device, and

Fig. 9 is a partial longitudinal sectional view

thereof and showing the same just after the insertion of a rivet into the work opening.

As shown in Figs. 1 to 3 inclusive which illustrate one embodiment of the invention, my improved rivet placing device is provided with an elongated hollow member or tube 10 which forms a support or magazine adapted to contain a plurality of rivets 11 or other articles to be fed. The tube 10 is open at both ends thereof and has a longitudinal slot 12 in the wall thereof. A plunger 13 is adapted to be inserted through the open outer end 14 of the tube for engagement with the outer end of a series of rivets previously placed in the tube. The plunger 13 has a lug 15 which projects through the slot 12 and is movable therealong. A tension spring 16 is connected with the lug 15 and constantly applies a pulling force to the plunger 13 causing the latter to advance the rivets 11 along the tube 10 toward the inner or delivery end 17 thereof.

Adjacent its inner or delivery end the tube 10 has a bracket 18 soldered or otherwise fixedly mounted thereon. The bracket 18 preferably has a portion 18a surrounding or partially surrounding the tube 10 and a pair of spaced ears 18b and 18c projecting substantially radially of the tube. The ears 18b and 18c form a support for an elongated hollow cover 19 which is adapted to be releasably held in closed position adjacent the tube 10 by a spring clip 20 which is carried by the cover and engageable with the tube adjacent its outer end. The cover 19 is connected with the ears 18b and 18c by means of a transverse hinge pin 21 which permits the cover to be swung toward or away from the tube 10. Between the ears 18b and 18c there is provided a grooved roller or sheave 22 which is rotatably mounted on the hinge pin 21. The tension spring 16 extends around the grooved roller 22 and longitudinally within the hollow cover 19. The outer end of the tension spring 16 is suitably anchored to the cover 19 as by providing thereon an integral lug or tang 23 to which the outer end of the spring is connected.

The rivets 11 are releasably retained in the tube 10 by a plurality of resilient fingers 25 which are disposed relative to the delivery end 17 to engage the rivets in succession and to control the passage of the rivets therefrom. The resilient fingers 25 are carried by a sleeve or ring 26 which surrounds the delivery end of the tube 10 and have their inner or free ends deflected toward the axis of the tube so as to be in converging relation to each other. The tube 10 is longitudinally slidable within the ring or sleeve 26 and, during movement

of the tube toward the work 27 into which a rivet is to be inserted, the inner or delivery end of the tube engages the converging portions of the resilient fingers 25 and spreads the same apart to release the endmost rivet from the tube and permit such rivet to be projected into the work opening 28 by the force of the tension spring 16.

For use in producing the relative axial movement between the tube 10 and the sleeve 26, I provide the sleeve with thrust means which projects beyond the resilient fingers and, in this instance, is in the form of a pair of integral axially extending arms 29. The arms 29 are engageable with the surface of the work 27 and serve to hold the free ends of the resilient fingers 25 in spaced relation to the work so that they can be readily spread apart by the delivery end 17 of the tube without scraping on the work surface. The thrust members 29 preferably have laterally extending integral lugs 30 thereon providing a bearing surface for engagement with the work 27 and which is not likely to cause marring or scratching thereof. To prevent buckling or springing of the thrust members 29 I may provide backing or reinforcing arms 31 on the bracket 18 and which extend forwardly in overlying or guiding relation to the thrust members 29 as shown in Figs. 1 and 2.

Although the sleeve 26 and the delivery end 17 of the tube are relatively slideable for producing the desired opening and closing of the convergent fingers 25, it is necessary to hold the sleeve 26 against complete separation or removal from the tube 10 which would otherwise occur as the result of the action of the spring 16. For this purpose I provide one of the ears of the bracket 18, in this instance the ear 18c, with an angularly disposed resilient latch portion 32 which extends into one of the recesses or opening 33 between one pair of the resilient fingers 25 and forms a shoulder or stop which will be engaged by the sleeve 26. During the ordinary use of the device this latch will prevent the sleeve 26 from being pushed from the delivery end of the tube 10 but the resilient character of the latch will permit the sleeve to be removed from the tube whenever this is necessary or desirable for repair or replacement purposes. It will be noted that the latch 32 is spaced from the outer end 34 of the sleeve portion 18a of the bracket 18 so that such outer end and latch form a pair of shoulders or stops which engage the sleeve 26 and limit the extent of movement of the tube 10 within such sleeve.

It will be seen from the foregoing description that when the tube 10 has been charged with a series of the rivets 11 and they are subjected to feeding pressure by the plunger 13, the head of the innermost rivet will be engaged by the convergent ends of the resilient fingers 25 and the rivet will be held with the stem thereof projecting from the tip of the device, as shown in Figs. 1 and 2, ready to be inserted into the opening 28 of the work 27. When the stem of the rivet has been inserted into the work opening the tube 10 is shifted toward the work by sliding movement within the sleeve 26 to cause the delivery end 17 to engage the convergent portions of the resilient fingers and spread the same apart sufficiently to permit passage of the head of the rivet as shown in Fig. 3. When the rivet head moves past the resilient fingers the rivet is projected or snapped into the work opening by the action of the spring 16. Thereupon the tube 10 is released, and under the contracting action of the resilient fingers against the delivery end 17, the tube moves rearwardly in the sleeve 26 and the resilient fingers

engage the head of the next rivet and hold the same in readiness for insertion into another opening of the work. When additional rivets are to be inserted into the tube 10 the plunger 13 can be removed through the open end 14 by stretching the spring 16 as indicated in construction lines in Fig. 2.

In Figs. 4 and 5 I show a modified form of my rivet feeding device in which the thrust members 36 are not formed integral with the sleeve 37 carrying the convergent resilient fingers 38 but are carried by a ring 39 surrounding the delivery end 40 of the tube 41 and lying within the annular group of resilient fingers. The sleeve 37 is contracted as shown in Fig. 5 to form an annular shoulder 42 which is engaged by the ring 39 to enable the thrust members 36 to hold the ends of the resilient fingers 38 in spaced relation to the surface of the work 43. In inserting a rivet into the work opening 44 the tube 41 is moved toward the work and within the sleeve 37 and ring 39 so as to cause the convergent portions of the resilient fingers to be engaged and spread apart by the delivery end 40 of the tube thereby releasing the endmost rivet in the manner already explained above. The sleeve 37 and the ring 39 are retained on the delivery end of the tube by the resilient latch 45 of the bracket 46.

In the modified form of rivet feeding device shown in Figs. 6 and 7 the delivery end 58 of the tube 51 is movable in a sleeve 52 for engagement of such delivery end with the convergent resilient fingers 53 carried by such sleeve. In this form of the device the thrust member which engages the work is in the form of a hollow tip 54 formed of plastic or any other suitable material and which surrounds the sleeve 52 and houses the resilient fingers 53. The tip 54 is preferably made of plastic material so as not to mar the surface of the work and has a convergent end 55 provided with an opening 56 of a size to permit the passage of the rivets 57 therethrough. The converging end of the tip 54 is desirable because it reduces the area of the tip adjacent the surface of the work 58 and affords better vision of the work opening and facilitates the insertion of the stem of the rivet thereto. As shown in Fig. 6, the tip 54 has a flange or shoulder 59 thereon adapted to be engaged by a resilient arm 60 of the bracket 61 for preventing unintentional separation of the tip from the delivery end of the tube. The sleeve 52 is also provided with an annular shoulder or flange 62 against which the end of the tip 54 engages for transmitting thrust to the sleeve for holding the latter while the tube 51 is advanced toward the work for expanding the resilient fingers.

In Figs. 8 and 9 another modification of the invention is illustrated which is similar to the form illustrated in Figs. 6 and 7 but in which the hollow tip 65 is retained on the delivery end 66 of the tube 67 by providing the tip with an axially extending slot or recess 68 in which a resilient arm or latch 69 engages. The latch 69 is carried by the ear 70 of the bracket 71. The hollow tip 65 forms a thrust member for a sleeve 72 which surrounds the delivery end of the tube and carries the convergent resilient fingers 73 for releasably retaining the rivets 74 in the tube. The hollow tip 65 can be formed of any suitable material and is preferably made of plastic so as to prevent marring of the surface of the work 75.

From the foregoing description and the accompanying drawings it will now be readily understood that I have provided improved rivet

feeding devices with which rivets or the like can be easily and rapidly inserted into work openings. It will be seen also that the novel means provided for the releasing of the individual rivets from the device is not likely to become jammed or to cause marring of the surface of the work.

While I have illustrated and described my improved rivet feeding devices in considerable detail it will be understood, of course, that I do not wish to be correspondingly limited but regard my invention as including all changes and modifications coming within the scope of the appended claims.

Having thus described my invention I claim:

1. In a device for feeding rivets or the like, an elongated hollow member forming a support for a plurality of rivets and having a delivery end, means for urging the rivets toward said delivery end, and resilient fingers disposed relative to said delivery end for releasably retaining the rivets in said support, said support being movable to engage and spread said fingers for releasing a rivet from the support.

2. In a device for inserting rivets or the like in work openings, an elongated hollow member forming a support for a plurality of rivets and having a delivery end, means for urging the rivets toward said delivery end, and a thrust member engageable with the work and having a plurality of resilient fingers thereon for releasably retaining the rivets in said hollow member, said hollow member being movable relative to said thrust member for engaging and spreading said fingers.

3. In a device for inserting rivets or the like in work openings, an elongated hollow member forming a support for a plurality of rivets and having a delivery end, means for urging the rivets toward said delivery end, resilient fingers disposed relative to said delivery end for releasably retaining the rivets in said hollow member, and thrust means engageable with the work for holding said resilient fingers in spaced relation to the work, said hollow member being movable relative to said thrust means and engageable with said resilient fingers for spreading the same.

4. In a device for feeding rivets or the like, a tube adapted to contain a plurality of rivets and having a delivery end, means for urging the rivets toward said delivery end, and a sleeve surrounding said tube adjacent said delivery end and having convergent resilient fingers adapted to releasably retain the rivets in said tube, said sleeve and tube being relatively movable for causing said delivery end to engage and spread said fingers.

5. In a device for feeding rivets or the like, a tube adapted to contain a plurality of rivets and having a delivery end, means for urging the rivets toward said delivery end, a sleeve surrounding said tube adjacent said delivery end having convergent resilient fingers adapted to releasably retain the rivets in said tube, and having a thrust member extending beyond said resilient fingers and engageable with the work, said sleeve and tube being relatively movable for causing said delivery end to engage and spread said fingers.

6. In a device for feeding rivets or the like, a tube adapted to contain a plurality of rivets and having a delivery end, means for urging the rivets toward said delivery end, a sleeve surrounding said tube adjacent said delivery end and having convergent resilient fingers adapted to releasably retain the rivets in said tube, said sleeve and tube being relatively movable for causing said delivery end to engage and spread said fingers, and retaining means connecting said tube and sleeve so as to permit said relative movement but preventing separation of the sleeve from the tube.

7. In a device for feeding rivets or the like, a tube adapted to contain a plurality of rivets and having a delivery end, means for urging the rivets toward said delivery end, and a hollow member surrounding said delivery end and having a thrust portion engageable with the work and convergent resilient fingers for releasably retaining the rivets in said tube, said tube and hollow member being relatively movable to engage said delivery end with said convergent fingers for spreading the latter.

8. In a device for feeding rivets or the like, a tube adapted to contain a plurality of rivets and having a delivery end, means for urging the rivets toward said delivery end, a sleeve surrounding said tube adjacent said delivery end and having convergent resilient fingers adapted to releasably retain the rivets in said tube, and a hollow tip surrounding said sleeve and having an opening for passage of the rivets, said tip being engageable with the work and adapted to transmit thrust to said sleeve, said tube and sleeve being relatively movable for causing said delivery end to engage and spread said fingers.

9. A device for feeding rivets to work openings comprising a tube adapted to contain a plurality of rivets and having a delivery end, a bracket mounted on said tube adjacent said delivery end, means for urging the rivets toward said delivery end, a cover connected with said bracket and extending along said tube, and a sleeve surrounding said delivery end outwardly of said bracket and having convergent resilient fingers for retaining said rivets in the tube, said sleeve and tube being relatively movable for causing said delivery end to engage and spread said fingers.

10. A device for feeding rivets to work openings comprising a tube adapted to contain a plurality of rivets and having a delivery end, a bracket mounted on said tube adjacent said delivery end, means for urging the rivets toward said delivery end, a cover connected with said bracket and extending along said tube, a sleeve surrounding said delivery end inwardly of said bracket and having convergent resilient fingers for retaining said rivets in the tube, said sleeve and tube being relatively movable for causing said delivery end to engage and spread said fingers, and means connected with said bracket and adapted to prevent separation of said sleeve from said tube.

LLOYD G. SPETH.
